UNITED STATES PATENT OFFICE.

HUGO A. BUCCINI, OF PHILADELPHIA, PENNSYLVANIA, ASSIGNOR TO VICTORY LAMP COMPANY, OF PHILADELPHIA, PENNSYLVANIA.

DESIGN FOR AN ELECTRIC-LIGHTING-FIXTURE RING.

Application filed December 19, 1927. Serial No. 24,536. Term of patent 3½ years.

To all whom it may concern:

Be it known that I, HUGO A. BUCCINI, a citizen of the United States, and a resident of Philadelphia, county of Philadelphia, State of Pennsylvania, have invented a new, original, and ornamental Design for Electric-Lighting-Fixture Ring, of which the following is a specification, reference being had to the accompanying drawing, forming a part thereof.

In the drawings accompanying this application:

Figure 1 is a plan view of the electric light-

ing fixture ring upon only a portion of which the ornamentation is shown completed, it being understood that the unornamented portion of the ring involves a mere repetition of the ornamentation shown.

Figure 2 is a side view showing a section of the ring in enlarged detail.

Figure 3 is a transverse section of the ring, this section being shown in dotted lines.

I claim:

The ornamental design for an electric-lighting fixture ring as shown and described.

HUGO A. BUCCINI.
